UNITED STATES PATENT OFFICE.

FRANZ CARL TEUFL, OF OIL CITY, PENNSYLVANIA, ASSIGNOR TO GENERAL ELECTRIC COMPANY, A CORPORATION OF NEW YORK.

PUMP.

1,112,339.

Specification of Letters Patent. Patented Sept. 29, 1914.
Application filed April 16, 1913. Serial No. 761,478.

To all whom it may concern:

Be it known that I, FRANZ CARL TEUFL, a subject of the Emperor of Austria-Hungary, residing at Oil City, county of Venango, State of Pennsylvania, have invented certain new and useful Improvements in Pumps, of which the following is a specification.

The present invention relates to pumps and more especially to pumps for supplying fuel under high pressure to internal combustion engines operating on the high compression plan.

The object of my invention is to provide a pump of improved construction, and for a consideration of what I believe to be novel and my invention attention is directed to the accompanying description and claims appended thereto.

In the accompanying drawing, which is illustrative of my invention, Figure 1 is a view in side elevation of an internal combustion engine equipped with my improved pump; Fig. 2 is a longitudinal section of the pump; Fig. 3 is a transverse section through the means for actuating the cut-off valve, and Figs. 4, 5 and 6 are detailed views illustrating the different positions of the cut-off valve under different conditions of load.

Fig. 1 illustrates an engine of any suitable construction comprising a base 10 and a main crank shaft 11. On top of the base is a cylinder 12 containing a piston which is connected to the main shaft in the ordinary way. I have shown only one cylinder, but it is to be understood that as many cylinders may be provided as are desired. I may use one pump for all of the cylinders, but preferably a pump is provided for each cylinder. Mounted in the head of the cylinder is a sprayer or fuel injector 13 of any suitable construction. Fuel is or may be injected from the sprayer to the cylinder by compressed air admitted to the pipe 14 from any suitable source of supply. For simplicity I have omitted the fuel valve and its actuator. 15 indicates the stem of the exhaust valve which is actuated by a rocker arm 16 from the half speed cam shaft 17 in the usual way. 18 indicates a conduit for carrying off the exhaust gases. The cam shaft 17 is mounted in bearings carried by brackets attached to the base of the engine. The bracket also

supports the cylinder 19 of the pump. Situated in back of the pump cylinder is a vertical shaft 20 that is driven by the cam shaft. On the upper end of this shaft is a speed governor 21 of any suitable construction. 22 indicates the sliding collar of the speed governor which is moved up and down by the governor weights as the speed of the engine changes. 23 indicates a governor lever which is connected to the cutoff valve of the pump as will be described more fully hereinafter.

Referring to Fig. 2, 19 indicates the pump cylinder and located therein is a hollow plunger 24 which has one or more ports 25 and a seat 26 for the cutoff valve 27. Just above the seat are one or more ports 28 in the plunger which communicate with the pump chamber 29. Surrounding the upper end of the stem of valve 27 is a collar 30 in which the valve is free to slide. The collar limits the downward movement of the cutoff valve, but has no effect upon its upward movement. The position of the collar is determined by the speed governor acting through a forked arm 31 which is mounted on the rock shaft 32. The rock shaft is mounted in bearings in the pump casing or cylinder and is suitably packed to prevent leakage. On one end of the rock shaft is an arm 33 that is connected by the rod 36 with the governor actuated lever 23. As the speed of the engine changes the collar 30 is moved up or down and the period of closing of the cutoff valve is, therefore, changed. I may depend upon gravity to close the valve 27 or the action of gravity may be supplemented by a light compression spring 37. Mounted on top of the pump cylinder is a fitting containing an overflow or relief valve 38 which is normally held against its seat by a sliding member 39 and a relatively stiff and adjustable spring 40. When the valve is opened by reason of a predetermined pressure in the chamber 29, as it is on each working stroke of the plunger 24, the excess fuel escapes by the pipe 41 back to the tank or other source of supply. The lower end of the plunger is provided with a suitable packing 42, and is actuated by an eccentric or crank 43 mounted on the cam shaft 17 and by a connecting rod 44. 45 indicates a ball suction valve and 46 a ball discharge valve. Leading to the suction valve is a conduit that

is connected to a tank or other source of supply, and leading from the discharge valve is a conduit 47 which conveys fuel under relatively high pressure to the sprayer or injector 13. Preferably the supply tank will be arranged to feed fuel by gravity to the pump. 48 indicates a passage that is in communication with the ball valves and with the port or ports 25 in the pump plunger. 10 Surrounding the plunger in the region of movement of the ports 25 and separated therefrom by a space, is a gland 49 containing orifices 50 through which fuel enters the plunger on the suction stroke and is discharged therefrom on the working stroke. 15 Above and below the gland are disks 51 which are seated on packing material surrounding the plunger and serve to hold the gland in place. 20 The action of my improved pump is as follows: As the plunger moves downwardly from the inner end of its stroke the cutoff valve 27 is opened by the pressure difference acting on opposite sides thereof. This 25 is due to the fact that as soon as the plunger starts to move downwardly it increases the cubical contents of the pump chamber 29, thereby tending to create a vacuum therein. The valve 27 follows the movement of 30 the plunger more or less closely due to the action of gravity and spring 37 until the shoulder on its upper end strikes the collar 30 whose position is determined by the governor. As soon as the valve opens, fluid 35 from the source of supply flows past the suction valve 45 into the passage 48 and orifices 50 through the port 25 into the plunger and into the chamber 29 through ports 28. This action continues until the plunger 40 reaches its lowest position. On the upward or working stroke of the plunger the suction valve 45 closes and the fluid displaced by the plunger is forced downward through the interior of the plunger and port or ports 45 25 into the passage 48, thence past the valve 46 into the pipe 47, from which it flows to the sprayer or injector 13. This action continues until the seat 26 on the plunger engages the lower end of the cutoff valve 27. 50 As soon as this happens the supply of fuel to the engine is cut off. Since this closing of the valve take place before the end of the plunger stroke, it follows that means must be provided to take care of the excess 55 fuel discharged by the pump. Such a means is found in the overflow or relief valve 38 that opens in response to pressure in the pump chamber 29 and discharges the excess through the pipe 41 to the tank or other 60 source of supply. It will be noted that the pump begins to deliver fuel at the same point on each stroke, *i. e.*, at the beginning thereof, and that the termination of the effective pump stroke is regulated by the 65 seating of the cutoff valve 27 which may be

earlier or later, depending upon the load on the engine. The time of closing of the valve is determined by the position of the collar 30, the latter being set by the action of the speed governor 21.

In Fig. 4 is shown the relation of the parts when the engine is operating under full load conditions; that is to say, the valve 27 does not close until nearly the end of the working stroke of the plunger.

Fig. 5 is a similar view showing the position that the valve occupies for partial loads, say one-half load for example.

In Fig. 6 is shown the relation of the valve when the engine is operating under light load conditions; that is to say, the time of closing of the cutoff valve 27 with respect to the stroke of the plunger is earlier. The effect of this of course is to decrease the amount of fuel supplied to the engine.

My improved pump mechanism has the advantage that the amount of fuel required by the engine is regulated by the action of the plunger and the cutoff valve 27. Also that in the operation of the pump there is no force applied to, or reaction upon the governor parts. This is important because it permits the use of a small governor, said governor being required only to overcome the friction on the rock shaft 32 and its stuffing boxes. The overflow or relief valve 38 discharges all of the excess fuel not required by the engine. The opening or closing of this valve earlier or later with respect to the plunger stroke depends upon the time of closing of the cutoff valve 27. That is to say, when the valve 27 closes earlier, the valve 38 will open earlier and hence a greater amount of fuel will be returned to the supply tank through the pipe 105 41. Conversely a later closing of the valve 27 will mean a later opening of valve 38 and hence less fuel will be returned to the tank. This arrangement also has the advantage that the pump will be cleaned on each discharge stroke, and hence any air or foreign gases instead of being trapped in the pump chamber will be carried off with the fuel through the pipe 41. The parts are so designed that even at maximum overload there 110 will be a certain small amount of fuel pass through the valve 38. It will be also noted that the time or beginning of the discharge stroke of the pump is invariable, and that it is absolutely independent of the speed 115 governor. Furthermore, it will be noted that the adjustment of the cutoff valve 27 is determined by the speed governor and is not dependent upon the position of the plunger.

The feature of having the plunger begin to discharge fuel at the same period or portion of its working stroke under all conditions is of particular importance where the pump is provided with a number of plun- 120 125 130

gers, each supplying fuel to its own injector, said injectors being in different engine cylinders. In other words all of the injectors will begin to receive fuel at the same instant, and hence the proper relation between the parts can be determined with accuracy.

In accordance with the provisions of the patent statutes, I have described the principle of operation of my invention, together with the apparatus which I now consider to represent the best embodiment thereof; but I desire to have it understood that the apparatus shown is only illustrative, and that the invention can be carried out by other means.

What I claim as new and desire to secure by Letters Patent of the United States, is:—

1. In a pump, the combination of a cylinder, a hollow plunger therefor, an actuator for the plunger, conduits conveying fluid to the cylinder and the discharge therefrom, and a valve located in the cylinder that cooperates with the plunger to cut off the discharge of fluid from the cylinder.

2. In a pump, the combination of a cylinder, a hollow plunger therefor, an actuator for the plunger, conduits conveying fluid to the cylinder and the discharge therefrom, a valve located in the cylinder that cooperates with the plunger to cut off the discharge of fluid from the cylinder, and an overflow valve which opens after the cut-off valve is seated.

3. In a pump, the combination of a cylinder, a hollow plunger having an inlet port and a valve seat, an actuator for the plunger, conduits conveying fluid to the cylinder and the discharge therefrom, a valve located in the cylinder which engages said seat at some portion of the plunger stroke to cut off the discharge from the cylinder, and means for determining the time of closing of the cutoff valve with respect to the stroke of the plunger.

4. In a pump, the combination of a cylinder, a hollow plunger therefor through which fluid passes from the cylinder on its discharge stroke, an actuator for the plunger, conduits conveying fluid to the cylinder and the discharge therefrom, a valve located in the cylinder which cooperates with the plunger to cut off the discharge of fluid from the cylinder, and means for adjusting the valve to determine the time of closure thereof and regulate the amount of fluid discharged on each plunger stroke.

5. In a pump, the combination of a cylinder, suction and discharge valves therefor, a hollow plunger, an actuator for the plunger, a cutoff valve that cooperates with the plunger to determine the amount of fluid delivered on each plunger stroke, means for determining the time of closing of the cutoff valve, and a pressure actuated relief valve

that opens to relieve the cylinder of fluid as the plunger continues its stroke after the cutoff valve is seated.

6. In a pump, the combination of a cylinder, suction and discharge valves therefor, a hollow plunger that has a port at one end and a valve seat at the other, an actuator therefor, a cut-off valve that enters and is guided by the wall of the plunger and engages said seat to cut off the discharge of fluid from the inside of the plunger to the discharge valve, a means for adjusting the cutoff valve, and a pressure actuated relief valve.

7. In a pump, the combination of a cylinder, a hollow plunger therefor, an actuator for the plunger, conduits conveying fluid to and from the cylinder, a valve located in the cylinder that co-operates with the plunger to determine the point of cut-off, and a speed governor that adjusts the valve.

8. The combination with an internal combustion engine of a fuel pump therefor comprising a cylinder, a hollow plunger, an actuator for the plunger, conduits conveying fuel to and from the cylinder, inlet and outlet valves in the conduits, a valve in the cylinder that seats on the plunger to determine the point of cut-off, a relief valve that opens after the cutoff valve closes, and a speed governor driven by the engine that regulates the closing of the cut-off valve.

9. The combination of an internal combustion engine with a fuel pump therefor comprising a cylinder, suction and discharge valves therefor, a hollow plunger in the cylinder which begins to deliver fuel through the discharge valve at the same period on each working stroke, an actuator for the plunger which imparts to it a stroke of constant length and in the same region, a cut-off valve located in the cylinder which is seated on the plunger at each working stroke, means for adjusting the position of the valve within the cylinder so that it will be seated earlier or later, and means receiving fuel from the pump during the working stroke and after the cutoff valve is seated.

10. In a pump, the combination of a cylinder, a plunger therefor, an actuator for the plunger, inlet and outlet passages for conveying fluid to and from the cylinder, suction and discharge valves in said passages controlling the flow of fluid therethrough, valve means located in said chamber and controlled by the plunger for cutting off communication between the chamber and the outlet passage, and means for receiving the fluid displaced after said valve means has closed.

11. In a pump, the combination of a cylinder having a pump chamber therein, a plunger therefor, an actuator for the plunger, conduits having suction and discharge valves therein, said plunger having a pas-

- 4
- sage therethrough which connects said conduits with the pump chamber, and a valve for closing said passage to control the quantity of fluid delivered by the pump.
- 6 12. In a pump, the combination of a cylinder having a pump chamber therein, a plunger therefor, an actuator for the plunger, conduits having suction and discharge valves therein, said plunger having a passage therethrough which connects said conduits with the pump chamber, a valve for closing said passage, means for varying the time of closing of said valve, and means for receiving the fluid delivered by the pump
- 10 after the passage is closed.
13. In a pump, the combination of a cylinder having a pump chamber therein, a plunger therefor, said plunger having a passage therethrough which communicates with the chamber, suction and discharge conduits which communicate with the chamber through said passage, a valve seat on the plunger, a valve in the chamber which engages the seat to cut off communication be-
- 15 tween the conduits and the chamber, and means for moving the valve relative to the seat to vary the time of closing.
14. In a pump, the combination of a cylinder having a pump chamber therein, a plunger therefor, said plunger having a passage therethrough which communicates with the chamber, suction and discharge conduits which communicate with the chamber through said passage, a valve seat on the plunger, a yieldingly supported valve in the chamber which engages the seat to cut off communication between the conduits and the chamber, said valve being biased toward said seat, and an adjustable stop for limiting the movement of the valve toward the seat.
